UNITED STATES PATENT OFFICE

WILLIAM C. MCCOY, OF SHAKER HEIGHTS, OHIO, ASSIGNOR TO THE CLEVELAND TRUST COMPANY, OF CLEVELAND, OHIO, A CORPORATION OF OHIO

PISTON

Application filed October 25, 1926. Serial No. 143,878.

This invention relates to pistons for internal combustion engines and particularly to composite pistons embodying separately formed head and skirt elements.

5 One of the objects of this invention is to provide a piston structure of inexpensive design in which the head is formed of an aluminum alloy casting, or other light weight metal that is a relatively good conductor of 10 heat, and the skirt separately formed of pressed steel or other suitable material.

Another object of the invention is to provide a piston structure having the advantages 15 of the heat conductivity of aluminum and the operational advantages of a skirt of relatively thin material of great strength, minimum weight, and of approximately the same coefficient of thermal expansion as the cylinder in which the piston is to be used.

20 An additional object of the invention is to provide a head and skirt structure in which the skirt is pivotally related to the head in order that each element of the piston may take separate adjustment relative to the 25 cylinder sleeve, to thereby minimize wear in the ring grooves incident to tilting of the piston in the cylinder and to obtain uniform bearing over the working faces of the piston skirt.

30 An additional object of the invention is to provide a skirt structure that may be formed of thin walled seamless steel tubing.

A further object of the invention is to provide a piston structure in which the temperature 35 of the working faces of the skirt and the thermal enlargement of the skirt are primarily controlled by the temperature of the cylinder walls of the piston.

Another object of the invention is to so connect 40 the piston skirt to the piston head as to substantially prevent distortions of the skirt through the thermal expansion of the head.

In the piston herein proposed, the head, with boss supporting portions integral therewith 45 constitutes an independently formed portion of the piston. This portion of the piston is herein referred to as the head element. It is preferably formed of an aluminum alloy or of other material having 50 physical characteristics that are particularly

desirable for the head element. The piston skirt is preferably formed from thin walled seamless steel tubing or other desirable material that can be conveniently so cut and formed as to act as a cross head or guide for 55 the side thrust imposed on the connecting rod. The skirt element is formed of thin walled material that will more closely follow the temperature of the side wall of the cylinder and maintain a substantially 60 uniform clearance at all operating temperatures.

The various objects and advantages of constructing pistons in accordance with this invention will be apparent from a consideration 65 of the accompanying drawings, wherein:

Figure 1 is a side elevational view, looking in the direction of the boss, of the separately formed piston head and wrist pin connections therefor. 70

Fig. 2 is a side elevational view, taken transversely of the boss with parts broken away and shown in section through the wrist pin axis, of a piston structure constructed in accordance with this invention and embodying 75 the form of piston head shown in Fig. 1.

Fig. 3 is an end plan view, with parts broken away and shown in section through one of the wrist pin bosses, of the skirt element of piston shown assembled with the piston head in Fig. 2. 80

Fig. 4 is a side elevational view of the piston skirt shown in Fig. 3 and taken in the direction of the wrist pin boss. 85

Fig. 5 is a side elevational view, with parts broken away and shown in section through one of the boss elements, of a modified form of piston constructed in accordance with 90 the invention.

Fig. 6 is a side elevational view, with parts broken away and shown in section through one of the boss elements, of a modified form of skirt structure that is adapted to be used 95 in a piston of the character herein proposed.

Fig. 7 is a transverse sectional view of the piston skirt shown in Fig. 6 taken substantially on line 7-7 of Fig. 6 and looking in the direction of the arrows. 100

Fig. 8 is a fragmentary top plan view of one of the skirt bosses.

The piston head and skirt structure are independently formed of different materials. 5 The head structure, with boss supporting portions extending therefrom, is preferably cast from aluminum or aluminum alloys having relatively high coefficient of heat conductivity. A metal having lightness, strength 10 and relatively high heat conductivity is preferable for use in piston head structures in order that heat may be readily dissipated from the piston head to the side walls of the cylinder through the piston rings, and also 15 in order that the head and boss supporting portions may be of very light weight although of great strength. The material should also be suitable for casting in permanent molds. Of the commercially known 20 metals, aluminum and aluminum alloys are believed to most adequately meet these requirements. The piston skirt, on the other hand, is preferably formed of thin sheet steel that can be readily formed. The skirt could, 25 however, be formed of other desirable wear resisting metals having thermal expansible characteristics suitable for use in cylinders of different physical characteristics.

The head portion of the piston, which is 30 particularly shown in Fig. 1, comprises a ring supporting portion with suitable ring grooves 1 that are formed therein, and a wrist pin supporting boss portion 2 that is connected to the remainder of the structure by suitable 35 depending webs 3 that are respectively reinforced by a strengthening rib 4.

The piston skirt, which is preferably formed of thin walled seamless steel tubing for use in cast iron or steel cylinder sleeves, 40 comprises a body portion preferably of cylindrical form that has inwardly bent portions 6 that constitute wrist pin supports for the skirt elements. The inwardly bent portions 6 are separated from the cylindrical 45 side wall of the tubing by transverse slots that permit the portions 6 to be pressed inwardly to form thereon a flanged boss carrying portion 7. The inwardly extending reinforcing flange 8 of the boss portion of the 50 skirt is formed sufficiently wide to properly support a wrist pin or a wrist pin bearing. The skirt structure is sufficiently rigid to properly receive and transmit side thrust from the connecting rod to the cylinder wall 55 without material distortion. The skirt portion is preferably pivotally related to the head in order that the only stresses that are imposed thereon are the side thrusts that are transmitted directly from the wrist pin to 60 the skirt portion of the piston in the manner of operation of the cross head of the conventional form of reciprocating steam engine.

In the piston structure shown in Fig. 2 which embodies a head structure of the form 65 shown in Fig. 1 and skirt structure of the

form shown in Figs. 3 and 4 in assembled relation, a bushing 9 is mounted solely in the boss supporting portion 7 of the skirt to provide a suitable bearing for the wrist pin of the skirt that is entirely independent of the operation of the head. The maximum diameter of the boss carrying portions 2 of the head is sufficiently small to permit the piston head structure to be inserted through the open upper end of the skirt in order that the supporting boss element 7 of the skirt will lie within the boss portions 2 of the head. This is desirable in order that the thermal expansion of the head will not carry the boss supporting portions 2 of the skirt outwardly 75 therewith. In this form of piston, the use of a floating wrist pin, that is locked in place by some form of conventional spring ring adapted to be received in the grooves 10 of the boss portions 2 of the piston head, is preferred. 80

In the piston shown in Fig. 2 the skirt is independently supported from the wrist pin, and the piston head is pivotally related to the skirt in order that the only forces that are imposed upon the piston head will be longitudinally of the cylinder and also in order that there will be substantially no movement of the ring supporting portion of the piston head incident to the lateral tilting of the 90 piston in the cylinder. In the piston proposed, lateral shifting of the wrist pin incident to skirt clearances causes the head to pivot about the ring supporting portion 95 thereof without substantial lateral shifting 100 of the head.

In the conventional form of piston, the lateral side thrust that is taken by the opposed working faces of the skirt causes lateral shifting of the piston body with the 105 greatest range of movement in the zone of the ring carrying portion of the head. The lateral shifting of the piston rings in the ring grooves during operation necessarily accentuates the wear between the rings and 110 the ring grooves.

In the piston structure herein proposed, there is substantially no lateral shifting of the ring carrying portion of the piston head, and therefore there is substantially no movement of the piston rings in the ring grooves of the head except the movement incident to adjustment of the rings to differences in the cylinder bore. Such movement of the rings in the ring grooves is relatively small 115 as compared with the movement incidental to lateral shifting of the piston head in the cylinder in response to side thrust against the skirt of the piston when the head and skirt are rigidly connected together. This is particularly important in pistons formed of 120 aluminum and other light weight metal in which wear results from the movement of the piston ring in the ring grooves.

The form of piston shown in Fig. 5 has 130

a bushing 11 for the wrist pin that extends through both the boss supporting portion of the skirt and of the head. The bushing 11 is preferably a pressed fit in the skirt boss 5 and pivotally mounted in the boss supporting portion 2 of the head. This pivotal relation between the piston head and the skirt provides bearing parts, wherein the more expandable and hotter operating part lies outside of the bushing to thereby prevent binding between the parts from heat.

It may be preferred, however, to pivotally mount the skirt portion 12 on the bushing 11 and to press the bushing 11 tightly within the boss supporting portion of the head in order to obtain greater bearing area for the boss elements of the head. This form of pivotal connection is desirable if a split bronze skirt, such as that illustrated in Fig. 15, is used or if the piston skirt is of bronze for use in a cylinder of aluminum alloy or of other relatively high expandable material.

In the form of skirt shown in Fig. 5, a series of longitudinal slots 13 are provided in each of the connecting members that join the working faces of the piston skirt. These longitudinal slots relieve the tightening of the skirt in the cylinder sleeve through the flexibility of the boss supporting portions 25 of the skirt to thereby prevent binding of the piston skirt within the cylinder sleeve.

If desired, the piston skirt may also be formed with a longitudinal slot 15 extending the entire length of one working face of the piston skirt as shown in Fig. 6. A skirt of this character is adapted to be supported from a bushing of the character shown in Fig. 5 that has a working fit within the skirt or the boss element of the head, or from a bushing 9 of the character shown in Fig. 2.

An inwardly extending reinforcing flange 14 is preferably formed on the end portion of the skirt remote from the head, and a corresponding flange 14', with parts cut away 45 to admit the boss portions of the head, is formed on the upper end of the skirt. These flanges serve to stiffen the skirt and also to maintain the skirt in cylindrical form at all times. Such flanges can readily be formed on the piston skirt by spinning or other desired process prior to the longitudinal slitting of the piston skirt.

It will be evident from a consideration of the piston structure herein described, that the 55 skirt of the piston may be fitted as closely to the cylinder wall as the metal from which the skirt is formed warrants. This thin wall of the skirt and the separable character of the skirt, reduces heat flow from the head to the 60 skirt and causes the skirt temperature to be primarily controlled from the cylinder sleeve.

It is also important that the boss carrying portions of the skirt may be formed by pressing the side walls of a metal cylinder in-

wardly. If desired, the piston sleeve shown in Fig. 6 could be formed without a transverse slot underlying the boss by stretching the metal of the skirt to form the boss element.

The method of manufacture of the skirt from short lengths of steel or other metal tubing, by the process of progressively pressing the side wall of the tubing inwardly as the transverse cut is extended to form boss 70 carrying elements of the skirt from the side walls of the tube, is important. This is an inexpensive operation that provides a piston of accurate dimension, of great strength although sufficiently flexible to follow irregularities in the cylinder sleeve. Tubing suitable for such use can be had in relatively accurate sizes and, for engines of the less expensive design, the piston skirt could be formed as shown in Fig. 6 and the skirt used 75 in the engine substantially without prior grinding. The piston skirt could be sprung into the cylinder and caused to free itself by working in of the engine. As heretofore stated, the material from which the sleeve is 80 formed is primarily dependent upon the physical character of the piston skirt selected and the material of the cylinder sleeve. In a piston sleeve of the form shown in Fig. 6, the yielding character of the piston skirt will 85 accommodate mechanical tolerances in the manufacture of cylindrical sleeves.

Since the head of the piston is separately formed and since it does not involve any intricate coring, the expense of the casting of the head of the piston will be greatly reduced. The skirt of the piston, on the other hand, being formed of any desired character of 90 metal that is suitable for this use, may be made of thin walled material that is very 95 light in weight and that will be of such expandable character as to properly fit the cylinder wall with the desired clearance.

It will also be apparent to those skilled in the art that the general form of the piston, 100 independent of the pivotal relation of the head and skirt, and the method of its manufacture, is of considerable importance. In fact, if desired, the bushing element 11 could be used to rigidly unite the head and skirt elements. This is particularly true of the piston shown in Fig. 5 and Fig. 6.

If the piston head and skirt are rigidly secured together by the bushing 11, of Fig. 5, it is then preferable to form the skirt of a 110 suitable wear resisting bronze alloy of higher temperature coefficient of expansion than the cylinder in order that the separation of the boss elements of the skirt in response to thermal expansion of the head will not tend to 115 draw the thrust faces of the skirt toward each other as is well known in the art.

Bushings 9 or 11, for use in the piston, could be of die cast material, the fit of which is within allowed manufacturing tolerances. 120

Although I have described only a few preferred modifications of the invention, many other adaptations thereof can be produced without departing from the spirit or scope of the invention. I desire, therefore, that only such limitations shall be imposed on the invention as are set forth in the accompanying claims.

What I claim is:

- 10 1. A composite piston structure having a separately formed head provided with depending wrist pin bosses; a sheet metal skirt, inwardly offset portions formed in opposite walls of said skirt, and wrist pin bosses formed in said offset portions and adapted to be disposed between said bosses in said head.
- 20 2. A composite piston structure having a separately formed head provided with depending wrist pin bosses, a sheet metal skirt, inwardly offset portions formed in opposite walls of said skirt and having coaxial openings therein, and circular wrist pin supporting flanges integral with said offset portions and defining said coaxial openings, said wrist pin supporting flanges being disposed between said bosses in said head.
- 30 3. A composite piston structure having a separately formed head provided with depending wrist pin bosses, a sheet metal skirt provided with spaced transverse slots at opposite sides thereof, the portions of said skirt between said slots being inwardly bent and provided with coaxial openings, circular flanges integral with said inwardly bent portions and defining said openings, said flanges being disposed between said bosses in said head, and a wrist pin bushing extending through said bosses in said head and said circular flanges for pivotally connecting said head and skirt.
- 40 4. A composite piston structure having a separately formed head provided with depending wrist pin bosses, and a tubular skirt of a different metal provided with a pair of spaced transverse slots in opposite sides thereof, the portions of said skirt between said spaced slots being offset inwardly with respect to said skirt and provided with coaxial wrist pin receiving openings, said wrist pin bosses on said head being disposed between said offset portions and the circular portions of said skirt in axial alignment with said openings in said offset portions for receiving a wrist pin.
- 50 5. A composite piston structure having a separately formed head provided with depending wrist pin bosses, a sheet metal skirt provided with a pair of spaced transverse slots in opposite sides thereof, the portion of said skirt in each side between said spaced slots being inwardly offset with respect to the circular portion thereof and provided with an opening, and circular wrist pin supporting flanges integral with said offset portions and defining the said openings therein, said

depending wrist pin bosses being positioned between the walls of said skirt and said offset portion in axial alignment with said openings.

6. A tubular sheet metal skirt for a piston having a separately formed head, said skirt having a pair of spaced transverse slots in diametrically opposite faces thereof, the metal in each of said faces between said spaced slots being offset inwardly with respect to the metal above and below said slots and provided with a wrist pin receiving opening, and the metal defining said opening being bent perpendicular to said offset portion.

In testimony whereof I affix my signature.

WILLIAM C. McCOY.
